UNITED STATES PATENT OFFICE

137,894

DESIGN FOR A CLOTHESPIN

Walter J. Martin, Pittsburgh, Pa.

Application April 5, 1944, Serial No. 113,149

Term of patent 14 years

(Cl. D17—6)

To all whom it may concern:

Be it known that I, Walter J. Martin, a citizen of the United States, residing at Pittsburgh, in the county of Allegheny and State of Pennsylvania, have invented a new, original, and ornamental Design for a Clothespin, of which the following is a specification, reference being had to the accompanying drawing, forming part thereof.

I claim:

The ornamental design for a clothespin, as shown.

WALTER J. MARTIN.
